UNITED STATES PATENT OFFICE.

PASQUALE GIORDANO, OF BOSTON, MASSACHUSETTS.

FLYING-MACHINE.

1,030,994.

Specification of Letters Patent.

Patented July 2, 1912.

Application filed April 20, 1912. Serial No. 692,096.

To all whom it may concern:

Be it known that I, PASQUALE GIORDANO, a citizen of the United States, residing at Boston, in the county of Suffolk and State 5 of Massachusetts, have invented certain new and useful Improvements in Flying-Machines, of which the following is a specification, reference being had to the accompanying drawings.

10 This invention relates to new and useful improvements in flying machines and my object is to provide an aeroplane comprising a pair of stationary supporting planes and a plurality of movable planes carried there- 15 between.

A further object of the invention resides in providing a pair of ascending and descending planes, and a still further object resides in the provision of a plane for guiding 20 the device laterally, said latter planes being pivotally carried on one of the ascending and descending planes.

Still another object of the invention resides in providing a device which is extremely 25 simple and durable in construction, inexpensive to manufacture and one which will be positive and efficient in operation.

With these and other objects in view, the invention consists in the novel features of 30 construction, combination and arrangement of parts as will be hereinafter referred to and more particularly pointed out in the specification and claims.

In the accompanying drawings forming 35 a part of this application, Figure 1 is a top plan view of the machine partly in section. Fig. 2 is a side elevation of the same partly in section. Fig. 3 is a fragmentary front elevation of the device; and Fig. 4 is a fragmentary perspective view of the rear movable planes.

In describing my invention, I shall refer 40 to the drawings in which similar reference characters designate corresponding parts throughout the several views and in which—

1 and 2 indicate respectively the upper and lower supporting planes which are arcuate in transverse section and are 50 tapered from their forward to their rear ends, said planes being held in spaced relation with respect to one another by means of the vertical spacing rods 3 and bracing

wires 4 are secured to the various spacing rods and the side edges of the respective 55 planes 1 and 2 to further brace the same. Front and rear supporting wheels 5 are depended from the lower plane 2 in the usual or any preferred manner, said wheels being provided with shock absorbers, for obvious 60 purposes and extending longitudinally between said planes 1 and 2 and rotatably mounted in bearings 6 of certain of the vertical spacing bars 3 are a pair of shafts 7, the ends of which project slightly beyond 65 the front and rear ends of the planes 1 and 2 and have mounted thereon the front and rear propellers 8. These shafts 7 are adapted to be rotated by any suitable means, (not shown) from an engine 9 and it will be appreciated from this construction that the device may be readily propelled by the rotation of the propellers 8.

In order to provide for the ascension and descension of the device, I provide a pair of 75 ascending and descending planes 10 and 11, the same being disposed respectively at the forward and rear ends of the machine and extending transversely thereof. The forward movable plane 10 is pivotally engaged 80 at its front edge with the eyes 12 formed in the collars 13, which collars are engaged with the vertical spacing bars 3 upon which the forward bearings 6 are mounted. The rear movable plane 11 being substantially 85 the same width as the plane 10, extends beyond the side edges of the planes 1 and 2, in view of the tapering of said latter planes and said plane 11 is provided with the open longitudinal spaces 14 to receive there- 90 through, a pair of vertical spacing bars 3 at the rear end of the machine to which spacing bars said plane is pivoted on the central horizontal axis, by means of the pins 15.

It will be readily understood that it is 95 necessary in the operation of a flying machine of this character to have the movable planes 10 and 11 operate simultaneously in order to effect the ascension and descension of the machine and to this end, connecting 10 cables or other flexible connections 16 and 17 are extended longitudinally along the sides of the machine and crossed, the ends of said cables being engaged with the arms or projections 18 and 19 carried on the respective 10 planes 10 and 11 and extending above and

below the faces thereof. By crossing the cables or flexible connections 16 and 17, as described, the one end of each will engage the arm or projection above the one plane, 5 while the opposite end of each cable will engage the arm or projection below the face of the opposite plane, whereby it will be appreciated that an upward movement of the one plane will cause a downward movement of the other and vice-versa. In order 10 to provide for the manual operation and ready manipulation of these planes, I provide a steering column or lever 20 which is pivotally or otherwise oscillatingly mounted 15 on the frame of the plane 2 and has connected thereto one end of a connecting rod 21, the opposite end of said connecting rod being pivotally engaged with a depending projection 22 on the front edge of the plane 20 10 about mid-way thereof. This steering column or lever 20 is disposed immediately adjacent a seat 23 on the frame of the plane 2, whereby the same may be readily operated by the driver of the machine. I have 25 also provided for the guiding or lateral movement of the machine and to this end, an additional plane 24 is provided, the same being movably mounted on the plane 11 on an axis at right angles to the axis of said latter 30 plane. This plane 24 is substantially circular in design, and formed in sections, one of which is disposed above the plane 11, while the other is disposed below the same and the sections of this plane are held together and 35 are movable on an axis at right angles to the axis of the plane 11 by providing a stem or shank 25 on the lower section of the plane 24 which projects through a bearing or the like 26 in the central portion of the 40 plane 11, said shank being then extended through a bearing or sleeve portion 27 in the frame of the upper section of said plane, and held thereto by means of a nut 28. That portion of the shank 25 which extends 45 through the bearing 26 in the plane 11 is circular in cross section, while that portion of the same extending through the bearing or sleeve portion 27 is square as particularly shown in Fig. 2, whereby it will be understood that while this circular plane 24 will 50 move with the plane 11, the same will also oscillate independently of said plane 11 on an axis at right angles to the axis of the latter. In order to operate this plane 24, a 55 pair of cables 29 and 30 are provided, the inner end of each of which is engaged with said plane 24, while the opposite ends thereof, after being passed over pulleys 31 on the plane 11, and additional pulleys 32 on the 60 plane 2, at opposite sides of the column 20, are engaged with said lever or column 20. This steering column or rod 20, while being capable of an oscillating movement as described above, is also suitably mounted to 65 permit rotation of the same through the

medium of a hand wheel at the upper end thereof and thus it will be understood that the driver while operating the ascending and descending planes 10 and 11 through the oscillation of said lever, or column, 20, 70 may also guide the machine through this same column by the mere rotation of the same.

From the foregoing description of the construction of my machine, the operation 75 of the same will be readily understood and it will be seen that I have provided a flying machine whereby the operating parts are centered on a single operating lever or steering column, thus eliminating all complications. It will further be seen that I have provided a pair of movable planes for the ascension and descension of the same and have further provided movable planes in connection with one of the last referred to 80 movable planes. Furthermore, it will be observed that the last mentioned plane carried on the one movable plane is movable with respect to the plane carrying the same on an axis at right angles to the axis of the 85 latter and is further substantially circular and formed in sections. It will still further be seen that the device is one which is extremely simple and durable in construction, inexpensive to manufacture and one which 90 will be very efficient and useful in operation.

While I have particularly described the elements most well adapted to perform the functions set forth, it is obvious that various changes in form, proportion and in the 100 minor details of construction may be resorted to without departing from the spirit or sacrificing any of the principles of the invention.

Having thus described this invention, 105 what I claim is:—

1. In a flying machine, a pair of supporting planes spaced one above the other, front and rear movable planes pivoted on horizontal axes between said supporting planes, 110 a substantially circular plane formed in sections and mounted centrally of the rear movable plane and pivoted thereto, on an axis at right angles to the axis of the latter, means for the manual operation of said 115 movable planes, and means for the propulsion of the device.

2. In a flying machine, a pair of stationary planes tapered toward the rear ends thereof, spacing bars between said planes, 120 a forward movable plane pivoted on a horizontal axis to certain of the spacing bars, a rear movable plane provided with longitudinal slots adjacent the ends thereof through which certain other of the spacing bars extend, means to pivotally mount said rear movable plane on a horizontal axis to the last mentioned spacing bars, said last mentioned plane having the ends thereof projected beyond the side edges of the sup- 125 130

porting planes at the rear ends thereof, an additional plane formed in sections, means to pivotally mount said additional plane on a vertical axis on the rear movable plane, the sections of said additional plane being disposed above and below the faces of said rear plane and secured together at the pivotal axis thereof, means for the manual op-

eration of said movable planes, and means for the propulsion of the device.

10

In testimony whereof I hereunto affix my signature in the presence of two witnesses.

PASQUALE GIORDANO.
